HENRY KOCH, OF JAMAICA, AND FRIEDRICH H. N. WOHLERS, OF HEMPSTEAD, NEW YORK, ASSIGNORS TO DICTOGRAPH PRODUCTS CORPORATION, A CORPORATION OF VIRGINIA.

TELEPHONE RECEIVER.

Application filed January 8, 1924. Serial No. 684,952.

To all whom it may concern:

Be it known that we, HENRY KOCH and FRIEDRICH H. N. WOHLERS, citizens of the United States, residing at Jamaica and 5 Hempstead, respectively, in the county of Queens and State of New York, have invented certain new and useful Improvements in Telephone Receivers, of which the following is a full, clear, and exact description.

10 This invention relates to telephone receivers, particularly of the type commonly employed in radiotelephone and telegraph receiving sets and popularly known as loud speakers. The invention is in the nature of 15 an improvement upon the type of loud speaker disclosed in copending applications of Henry Koch, Serial No. 628,709, filed March 30, 1923, and Serial No. 661,596, filed September 8, 1923. In this type of loud 20 speaker, the volume of sound may be varied by varying the influence upon the diaphragm of an electromagnetic actuating unit and this invention comprehends means for simplifying or facilitating the initial adjustment 25 of the means for varying the influence of the electromagnetic unit upon the diaphragm.

An object of the invention is to provide 30 an improved telephone receiver construction, in which the initial adjustment of the volume varying means may be quickly and easily effected in a simple manner, which will, at the same time, be relatively simple in construction and easily assembled, and 35 which will readily permit subsequent adjustments of the volume varying means in case such subsequent adjustment becomes necessary. Other objects and advantages 40 will be apparent from the following description of an embodiment of the invention, and the novel features will be particularly pointed out hereinafter in claims.

In the accompanying drawing:

45 Fig. 1 is a sectional elevation through a loud speaker constructed in accordance with the invention;

Fig. 2 is a transverse section of the same, taken substantially along the line 2—2 of Figure 1; and

50 Fig. 3 is a sectional elevation of a portion of the speaker, the section being taken substantially along the line 3—3 of Figure 2.

In the illustrated embodiment of the invention, an amplifying horn 1 is supported 55 upon a suitable hollow base 2, with the small

end of the amplifier 1 communicating through an aperture 3 with the interior of the support or base 2. A plate 4 is secured against the inner face of the wall of the base having the aperture 3, and is provided 60 with an aperture 5 aligned with the aperture 3. A cup-shaped casing 6 is secured with its open end against the plate 4, and a diaphragm 7 is clamped between the open end of the casing 6 and the plate 4, suitable gas- 65 kets being disposed upon opposite faces of the diaphragm around its periphery so as to permit of free vibration of the diaphragm. A second cup-shaped casing 8 is disposed within and slidably in the casing 6, with its 70 open end at the open end of the casing 6.

The casing 8 is provided with a stud 9 extending freely rearwardly through an aperture 10 of the casing 6, and the outer end of the stud is threaded. A gear 11 is threaded upon the outer threaded end of the stud 9, and one or more washers 12 may be disposed between the gear 11 and the outer face of the wall of the casing 6 through which the stud passes. A suitable spring 13 is disposed between the inner end of the casing 8 and the abutting wall of the casing 6, so as to constantly and yieldingly urge the casing 8 toward the diaphragm and draw the gear 11 toward the casing 6. The gear 11, however, limits the movement of the casing 8 under the influence of the spring 13. In the embodiment illustrated, the spring 13 is in the nature of a leaf spring with a central aperture through which the stud 9 passes. 80 A pin 14 within the casing 6 projects through an aperture in the spring and also enters an aperture in the inner end wall of the casing 8, and thus serves to keep both casing 8 and the spring 13 from rotating 85 within the casing 6.

An electromagnetic actuating unit 15, having spaced pole pieces 16, is mounted in any suitable manner within the casing 8 so as to move therewith toward and from the 100 diaphragm 7. Suitable circuit wires 17 lead from the electromagnetic unit 15 through an aperture 18 in the base or support 2 for incorporation in any actuating circuit.

A shaft 19 is rotatably mounted in the 105 base or support 2 and carries, upon its outer end, an actuating button 20 and an indicating dial 21, by means of which the shaft may be rotated to various desired angular positions. The inner end portion 22 of the 110

shaft 19 is reduced in diameter and has a bearing in the casing 6. A gear 23 is mounted upon an intermediate shouldered portion 24 of the shaft 19 so as to slide freely thereon, and a key 25 is carried by the portion 24 of the shaft 19 in a position to enter a key slot 26 in the gear 23 when the latter is shifted endwise upon the intermediate portion against the portion of the shaft 19 of greatest diameter.

The gear 23, when keyed to the shaft, meshes with the gear 11 on the threaded end of the stud 9, so that whenever the button 20 is rotated, the gear 11 on the stud 9 will be rotated, and the rotation of the gear 11 will serve to move it endwise upon the stud 9. If the rotation of the gear 11 is in one direction it will draw the stud 9 through the casing 6 to various extents against the action of the spring 13, and this will carry the electromagnetic actuating unit away from the diaphragm 7 to lessen the influence of the unit thereon. When the rotation of the gear 11 is in the opposite direction the gear will tend to move along the stud 9 away from the casing 6, and thereupon the spring 13 will shift the stud inwardly and thereby carry the electromagnetic actuating unit 15 toward the diaphragm 7 to increase its influence thereon.

A helical spring 27 is placed upon the intermediate portion 24, under compression between the gear 23 and the casing 6, so as to constantly press the gear 23 against the shoulder formed between the intermediate portion 24 and the larger part of the shaft, in which position the gear will be keyed to the shaft. The helical spring will yield and permit movement of the gear 23 toward the casing 6 sufficiently to be disengaged from its key 25 and out of mesh with the gear 11. When this is done, the gear 11 may be freely rotated to give to the casing 8 and the electromagnetic actuating unit 15 an initial setting, relatively to the diaphragm 7, in which a desired initial effect will be obtained. When the gear 24 is released the spring 27 will shift the gear 24 into mesh with the gear 11 and into engagement with the key 25 of the shaft.

With this construction the mere rotation of the button 20 will serve to vary the volume of sound emitted by the diaphragm 7, by reason of the variation of the position of the electromagnetic actuating unit relatively to the diaphragm. When the parts are assembled in the factory, it is necessary to determine the proper initial setting of the electromagnetic actuating unit relatively to the diaphragm. For this purpose the circuit wires 17 are for adjusting purposes, connected into a suitable circuit having in the current flowing therein, variations corresponding to sound waves. The button 20 is rotated in a direction to cause an increase

in the influence of the unit upon the diaphragm until a tooth 28 of greater length than the other teeth of the gear 23 comes into contact with the teeth of the gear 11 and limits further rotation. While the diaphragm is being actuated by the variations in this current passing through the electromagnetic actuating unit, the gear 23 is shifted toward the casing 6 out of mesh with the gear 11. The gear 11 may then be rotated until the maximum volume of sound is obtained without the diaphragm striking the pole pieces of the unit. Thereupon the gear 24 is released and allowed to remesh with the gear 11.

It will be understood that this method of effecting an initial setting, is independent of the details by which the influence of the magnetic unit upon the diaphragm is varied, and that various changes in the details, herein described and illustrated for the purpose of explaining the nature of the invention, may be made by those skilled in the art within the principle and scope of the invention, as expressed in the appended claims.

Claims:

1. In a telephone receiver, a diaphragm, an electromagnetic actuating device for said diaphragm, movable relatively thereto for varying its influence thereon, means including a gear for producing such relative movement, a pinion meshing with and driving said gear, a support for said pinion permitting movement of the pinion into and out of meshing engagement with said gear, whereby when the pinion is out of mesh with the gear the latter can be independently operated to give the diaphragm and its actuating device an initial relative setting, and means by which the pinion may be rotated to cause a variation in the influence of the actuating device upon said diaphragm.

2. In a telephone receiver, a diaphragm, an electromagnetic actuating device for said diaphragm, movable relatively thereto for varying its influence thereon, means including a gear for producing such relative movement, a pinion meshing with and driving said gear, a support for said pinion permitting movement of the pinion into and out of meshing engagement with said gear, whereby when the pinion is out of mesh with the gear the latter can be independently operated to give the diaphragm and its actuating device an initial relative setting, means for yieldingly urging the pinion into meshing relation with said gear, and means by which the pinion may be rotated to cause a variation in the influence of the actuating device upon said diaphragm.

3. In a telephone receiver, a diaphragm, an electromagnetic actuating device for said diaphragm, means by which the influence of the actuating device upon the diaphragm may be varied, and including an operating

gear, means for operating said gear including a second gear meshing with the first gear, a shaft upon which the second gear is keyed so as to slide thereon and rotate therewith, a spring device for yieldingly pressing the second gear endwise along the shaft, and means for limiting endwise movement of the second gear by the spring device beyond a position in which it meshes with the first gear, said spring device yielding to permit movement of the second gear away from the limiting means and out of mesh with the first gear in order to enable an initial setting of the first gear independently of the second gear.

4. In a telephone receiver, a diaphragm, an electromagnetic actuating device for said diaphragm, means by which the influence of the actuating device upon the diaphragm may be varied, and including an operating gear, means for operating said gear including a second gear meshing with the first gear, a shaft upon which the second gear is keyed so as to slide thereon and rotate therewith, a spring device for yieldingly pressing the second gear endwise along the shaft, said shaft having thereon a shoulder against which said second gear is yieldingly pressed when in mesh with said first gear, said spring device yielding to permit movement of the second gear away from the shoulder when the second gear is shifted out of mesh with the first gear to enable an initial setting of the first gear independently of the second gear.

5. In a telephone receiver, a diaphragm, a casing at one end of which the diaphragm is mounted, an electromagnetic device mounted in said casing and movable toward and from the diaphragm, a gear in thread-

ed connection with the device and acting against the casing so that when the gear is rotated in one direction the device will be shifted in one direction relatively to the diaphragm, a spring device for shifting the electromagnetic device in the opposite direction when the gear is rotated in the opposite direction to release the electromagnetic device, a shaft bearing in said casing and having a shoulder thereon, a pinion keyed to the shaft for movement toward and from the shoulder, said pinion meshing with the gear when against the shoulder and out of mesh therewith when shifted away from said shoulder, means for yieldingly holding the said pinion against said shoulder and yielding to permit demeshing of the pinion and gear and thus enable an initial setting of the gear independently of the pinion and shaft, and an operating button on said shaft to enable its manual operation.

6. In a telephone receiver, a diaphragm, an electromagnetic actuating device for said diaphragm movable relative thereto for varying its influence thereon, means including a gear for producing such relative movement, a pinion meshing with and driving said gear, means by which the pinion may be rotated, and means whereby the operative connection between said last named means and the gear through the pinion may be broken to permit an initial setting to be given to the diaphragm and its actuating device.

In witness whereof, we hereunto subscribe our signatures.

HENRY KOCH.
FRIEDRICH H. N. WOHLERS.
